poration of California

Application March 13, 1935, Serial No. 10,890

8 Claims. (Cl. 250—36)

My invention relates to an electron beam oscillator, and more particularly to such an oscillator utilizing the time of flight of an electron. The apparatus and method is particularly adapted for the production of ultra high frequencies.

The principal object of my invention is to provide a means and method for producing ultra high frequencies.

Other objects of my invention are: to provide a cathode ray beam oscillator utilizing the time of flight of an electron; to provide a cathode ray oscillator wherein the means for deflecting a cathode ray beam are also the means for collecting the electrons in said beam; to provide a cathode ray tube wherein the electrons are deflected by the charge on the collecting anodes; to provide a cathode ray tube of simple construction and which is an automatic oscillator; to provide a cathode ray tube oscillator having a minimum of leads associated with the oscillating circuit; and to provide a cathode ray oscillator operating by virtue of the time elapsed during the passage of an electron through a predetermined path.

Other objects of my invention will be apparent or will be specifically pointed out in the description forming a part of this specification, but I do not limit myself to the embodiment of the invention herein described, as various forms may be adopted within the scope of the claims.

Referring to the drawings:

Figure 1 is a perspective view, in elevation, of a preferred form of cathode ray tube of my invention wherein the envelope walls have been cut away to show the internal elements.

Figure 2 is a diagram indicating the various positions of the beam during a complete cycle.

Figure 3 is a diagram, reduced to lowest terms, of a simple circuit in which my invention may be utilized.

Figure 4 is a perspective view similar to Figure 1, showing a modification of my invention wherein the impact area of the received beam is off-set.

In broad terms of method, my invention comprises generating a beam of cathode rays, deflecting said beam near the source, projecting said beam into space, and causing said beam to return to a position close to the plane of deflection, there to be collected. I prefer to cause the potentials produced by the collection of the beam to deflect the beam. Due to the time delay of the electron during its travel from the zone of deflection back to the zone of collection, I am

able to create an oscillating current in an external circuit. The operation of the tube depends upon the time delay between the deflection and the collection, and also on the fact that a deflection velocity received close to the source produces a much greater deflection than an equal velocity received as the electron returns to be collected.

In broad terms of apparatus, my invention comprises a pair of anodes and means for passing an electron beam through an aperture between them. I then provide means for imposing a retarding potential on said beam to cause it to change its course and return to be collected by the anodes. The potentials imparted to the two anodes by collection of the electrons causes deflection to take place. Proper adjustment of the time of flight will cause the beam to automatically oscillate from one anode to the other. A tuned circuit is preferably connected across the anodes.

The method and details of construction of my invention may be easily gathered from the following description:

Referring to Figure 1, showing a preferred form of my invention, a cylindrical envelope 1 is provided at one end with a reentrant stem 2. A press 3 of this stem carries a pair of cathode leads 4 supporting a linear cathode 5. An accelerating anode 6 provided with a linear aperture 7 is held by means of accelerating anode leads 8, so that the aperture 7 is immediately over and parallel with the linear cathode 5. In Figures 1 and 4 the electrodes have been separated more than they would be in actual practice, this larger separation being here shown for the sake of clarity in illustration. This combination of linear cathode and linear anode aperture will produce an electron beam collimated in such a way that the long dimension of the beam will be at right angles to the cathode and the slot, as described in the application above referred to.

Slightly above the accelerating anode I prefer to position a pair of semi-circular collecting anodes 9A and 9B. These anodes are provided with opposing up-turned lips 10, are in the same plane, and are positioned with the lips spaced slightly apart to form a beam slit 11 at right angles to the base of the cathode and so centered as to allow the collimated beam to pass between the two anode lips. The anodes 9A and 9B are supported by anode leads 12 sealed through the side walls of the tube.

At the other end of the tube I prefer to mount a field forming bar 14 mounted on an electrode

lead 15. I prefer to make this electrode of relatively small wire and mount it so that the bar will extend at right angles to the beam slit 11 between the anodes and parallel with the aperture 7 and the cathode 5. This comprises all the structure necessary inside the tube for the proper operation of the device.

As the structure shown in Figure 4 is very similar to that shown in Figure 1, it utilizes the same principle of operation and the same circuits, it will be described at this time. Here the envelope 4 is provided with the same accelerating anode 6 and linear cathode 5, with the exception that the cathode and accelerating anode assembly are off-set slightly toward one side of the tube. The two anodes 9A and 9B in this case are slightly overlapped and the lips 10 are short and extend only part way across the overlap, thus providing an off-center beam slit. Then, by means of a focusing electrode 16 supplied by a constant potential source 17, a small continuous bias is placed on the beam causing it to return in a position on the anodes where it does not have to pass over the slit 11 as the beam oscillates. In all other respects the two tubes are identical, and their operation will be described later. In both Figures 1 and 4 I have diagrammatically indicated the path of the beam by broken lines 17, and the impact area, covered by the beam as it returns to the anodes 9A and 9B, by a dotted line 18.

A circuit in which this tube may be utilized is shown, reduced to lowest terms, in Figure 3. An inductance 20 is shunted by a capacity 21 to form a tuned circuit, one end of which is connected through wire 22A to the anode 9A, and the other end is connected through wire 23B to the anode 9B. A center tap 24 of the inductance 20 is connected by means of wire 25 to the accelerating anode, and the two together are connected by wire 26 to a source of positive potential 27, the negative end of which goes directly through wire 29 to the bar electrode 14 and also through a resistor 30 to the cathode 5. As is quite customary in diagrams of this sort, no source of current is shown for the cathode 5.

It is believed that the operation of the device may be more readily understood by reference to the series of diagrams shown in Figure 2.

Let us assume that the circuit as shown in Figure 3 is adopted and that the potentials have just been applied. It should be noted that the accelerating anode 6 and both of the anodes 9A and 9B are at the same positive potential.

Electrons generated by the cathode 5 are accelerated through the aperture in the accelerating anode 6 and formed into a collimated beam. This beam is projected through the equi-potential space between the two anodes 9A and 9B and the anode 6, and through the beam slit 11. The electrons in the beam travel out toward the bar 14 against the retarding negative potential thereon, and turn at the top of their trajectory and return to the plane of the 9A and 9B anodes.

It will be obvious, of course, that the retarding potential shall be such that the electrons do not quite reach the bar 14; and that the length of path should be adjusted either by the potential on the bar or by the physical spacing of the bar from the anodes, in combination with the initial velocity of the electrons, so that the time required for the beam electrons to travel the distance of their course is either 1/2, 3/2, 5/2 etc. of the period of the oscillator.

At the instant of the first return of the elec-

trons to the 9A and 9B anodes, more electrons will be bound to fall on one than on the other. In diagram A of Figure 2 I have shown more electrons falling on 9B than on 9A. 9B therefore acquires a negative charge and 9A an equal and opposite positive charge. The lips of the anodes then act as deflecting plates, and the beam will be thrown to the left, as shown in diagram B. As soon as the returning electrons, however, start to arrive on 9A, the anode 9A changes from positive to become highly negative, as shown in diagram C. This change immediately deflects the beam toward 9B, but electrons are still returning to 9A. The stream, however, has been given the inclination toward 9B and as the intensity of charge rises, due to the full collection of the stream by 9A, maximum deflection is obtained in diagram C and the returning electrons start to move back again toward 9B. When they begin to arrive on 9B, as shown in diagram D, 9B accumulates the negative charge which immediately starts the deflection in the direction of 9A, as shown in diagram E, and the cycle is repeated as indicated in diagram F.

As plates 9A and 9B are connected to an oscillating circuit the oscillations set up therein by the collection of the electrons will be continuous, and all that is necessary for maximum output of sustained oscillations is that the time of flight be so regulated that the electrons will fall on one plate while being deflected near the source toward the other plate. The action might be compared in physical analogy to the result which would be obtained if a garden hose nozzle were held in the hand, directing a stream of water therefrom straight in the air. A slight horizontal oscillation given to the nozzle would cause the returning water to land on one side or the other of the nozzle, and it would be quite possible to reproduce the entire action with water if the water collected could be made to oscillate the nozzle, and the time of flight of individual drops of water be properly adjusted.

It will be noted that in the device shown in Figure 1 the returning electrons pass directly across the slit 11 and intermingle with the outgoing electrons, and that due to this fact there will be a slight time gap in the output energy as some returning electrons will pass back through the slit. I have avoided this action in the construction shown in Figure 4 by overlapping the plates and causing the returning electrons to travel in a path to one side of the slit. In this manner there is no loss of returning electrons nor do they, except at the bend in the path, intermingle with the outgoing electrons.

While both the outgoing and returning electrons are subject, in varying degrees, to the deflection potentials, the deflection velocity received as the electrons leave the accelerating anode produces a much greater deflection than an equal velocity received as the electrons return to a collecting anode. The displacement of the beam may thus be accomplished without difficulty.

The frequency produced by the device will vary as the square root of the voltage between the cathode 5 and the accelerating anode A, provided the bar electrode 14 is only slightly negative with respect to the cathode 5. If, however, the bar electrode 14 is made considerably more negative with respect to the cathode 5, by means of a battery or other arrangement, the frequency will vary in the reverse direction if a large flat plate is used instead of the bar 14. If, however, a field,

due to the electrode 14, which varies in strength directly as the distance from the accelerating anode 6 can be set up, the repelling force on the electron is directly proportional to the distance from the accelerating anode. A field of this type can be closely approximated by the use of the narrow bar electrode as shown. The difference of potential between this bar and the cathode may be adjusted by means of the resistance 30 to give the best compromise possible.

When these factors have been taken care of, we have the law of the spring pendulum fulfilled in which the resisting force is proportional to the displacement; and the period is independent of the amplitude. These conditions would make the frequency of the oscillator substantially independent of voltage. It is not, however, necessary that this law be exactly fulfilled in order to make the frequency independent of voltages over a small range. It is entirely practical to so arrange the fields and the potentials in the tube that the frequency will be constant over the normal range of the line fluctuations when the potentials fluctuate from converters attached to current mains. It will be apparent to all those skilled in the art that by proper adjustment of the resistance 30, to change the bias between the cathode 5 and the bar electrode 14, and using the proper travel distance and the proper voltage on the anodes to correspond with the frequency desired and fixed by the constants of the tuned circuit, that ordinary line voltage fluctuations will not change the frequency to an extent which would, in any way, be inimical to the practical operation of the device. If the bias on the bar 14 be tied in with the potential of the anodes, some compensation will occur.

The uses and advantages of the invention are obvious. It would of course be possible to build a device where the beam traversed a long tube, eventually landing on collecting anodes. Leads from these anodes, however, would have to be brought back along the tube to deflecting plates positioned near the source. The existence of these leads would immediately destroy the ability of the tube to oscillate at ultra high frequencies and for that reason deflecting the stream and collecting the electrons therein in substantially the same plane allows such leads to become nonexistent, the deflecting means and collecting means being the same piece of metal.

To carry the application of this device to its logical conclusion for the production of ultra high frequencies, the anodes 9A and 9B may be directly connected to the respective ends of a radiating di-pole, the size of which will control, in conjunction with a properly coordinated travel time, the frequency of oscillation. Furthermore, it is easily possible to modulate this oscillator by the use of a grid to control the current of the cathode ray beam. This grid would effect the amplitude of oscillation of the beam, giving a regenerative effect on the modulation, but it would not change the frequency.

As the time delay between deflection and collection determines the frequency, it will be obvious the frequency varies as

$$\sqrt{\frac{2E}{M}}$$

where E is the voltage on the bar 14. As this potential creates a greater influence on the frequency than any other single factor, it is important that the potential remain fairly constant.

If it is found that line fluctuations cause too great a change of potential on this bar, it is not diffi-

cult to maintain a very accurate fixed potential upon it by other means, as this electrode draws no current. Other means of stabilization will also be apparent to those skilled in the art.

As the frequency can be changed by the direct current potential of bar 14, it is quite obvious that the oscillator can be synchronized with other devices utilizing the charge on the bar 14 as a frequency control.

The actual physical dimensions of a tube necessary to obtain a given frequency should next be considered. The velocity V of an electron =

$$\sqrt{\frac{2EC}{M}}$$

where E is the electrostatic voltage, C is the charge on the electron in electrostatic volts, and M is the mass of the electron. If the anode potential is 3,000 volts, or 10 electrostatic volts, the mean velocity over the path is 1.63×10^9 centimeters per second. The time of flight at 66 megacycles is

$$\frac{1}{1.32 \times 10^8}$$

As $D=VT$ where V is velocity and T time, the total distance travelled by an electron is 12.4 cm. The distance one way is 6.2 cm. or 2.44 inches. It will be seen, therefore, that the tube is entirely practical and compact in its structure.

A tube such as the one shown in the drawings may be operated at one, three or five times the fundamental frequency, but is probably limited practically to the lower harmonics unless the region of deflection can be limited to a very exceptionally short distance from the accelerating anode. The shorter this distance the easier the tube will work on the higher harmonics.

Since the frequency which can be handled by this tube is determined to a degree by the time spent by the electrons between the deflecting plates, and the sensitivity to deflection goes up as the total time of flight of an electron increases, it is not advantageous to shorten the tube indefinitely for excessively high frequency operation. It has been found, however, that tubes of the construction shown with practical spacings will operate satisfactorily between 30 and 200 megacycles.

It is also possible to adapt the tube to produce much lower frequencies, and in case it is desired to use such lower frequencies I prefer to put a screen grid above the anodes 9A and 9B which is negative thereto but positive to the cathode. This will produce a long electron path at relatively low average velocities, and greatly increase the time of flight. It will be obvious that with this latter arrangement the deflection sensitivity will also be increased. It is possible by the use of such a grid to go below 10 megacycles.

It is therefore seen that my invention is limited in its production of high frequency oscillating current only by the loss of deflection sensitivity with very short paths, and in the production of low frequencies only by the ability to lay out a sufficiently long path. The limitation on the high frequencies may be, in certain desirable cases, removed by some sacrifice of efficiency, and the device may be used to supply a small oscillating current at an extreme high frequency where most of the energy is needed for deflection. The limited output may then be amplified by other means.

Within its wide range in the ultra high band, therefore, the device is an efficient and what might be termed an "easy" oscillator. It starts

into oscillation readily; it is not subject to the usual frequency variations; is ideally adapted for di-pole radiation; and is also ideal for operation at a long distance from the power supply, as on masts. The circuit is exceptionally simple, and the device, when attached to a di-pole, needs only filament and anode supply wires with no necessity for complicated circuits. The physical dimensions of the tube for extraordinary high frequencies may be made relatively large; accuracy of construction may thereby be obtained. No critical adjustments are necessary, and the device may be readily modulated.

I claim:

- 15 1. The method of producing sustained oscillations which comprises generating a beam of electrons, projecting said electrons into space, returning said electrons to a plane adjacent the source, collecting the electrons substantially in 20 said plane, and applying the charge produced thereby in the same plane to said beam to produce deflections thereof.
- 25 2. The method of producing sustained oscillations in a cathode ray tube having an electron source and a pair of collecting electrodes which comprises positioning said electrodes adjacent said source, directing electrons between said electrodes in a formed beam into space, returning said electrons to the plane of said electrodes and 30 utilizing the charge imparted to one of said electrodes by the collection of electrons thereon, to move said beam to cause electrons to return to the other of said electrodes.
- 35 3. In a cathode ray tube comprising an envelope containing a cathode and an anode for producing a cathode ray beam, a pair of collecting electrodes positioned relatively close to the source of said beam with the beam passing therebetween, means for returning the electrons to the plane of said collecting electrodes, and means for regulating the time of flight of said electrons to cause said beam to be collected by said electrodes alternately, said electrodes acting as deflectors when charged by collection.
- 40 4. In a cathode ray tube comprising an envelope containing a cathode and anode adapted to produce a cathode ray beam, a pair of electrodes separated to allow said beam to pass therebetween into space, means for returning said beam to the plane of said electrodes for collection,

the charge imparted to said electrodes thereby acting to deflect said beam, means for regulating the time of flight, and means for stabilizing the deflections.

5 5. In a cathode ray tube comprising an envelope containing a cathode and anode adapted to produce a cathode ray beam, a pair of electrodes separated to allow said beam to pass therebetween into space, means for returning said beam to the plane of said electrodes for collection, the charge imparted to said electrodes thereby acting to deflect said beam, means for regulating the time of flight, and means including a tuned circuit connecting said electrodes for stabilizing the deflections. 15

6. In a cathode ray tube comprising an envelope containing a cathode and anode adapted to produce a cathode ray beam, a pair of dual purpose electrodes separated to allow said beam to pass therebetween positioned close to the source 20 of said beam, means for producing an alternating deflection charge on said electrodes by collection of electrons from said beam, and means for regulating the frequency of deflection. 25

7. In a cathode ray tube comprising an envelope containing a cathode and anode adapted to produce a cathode ray beam, a pair of electrodes separated to allow said beam to pass therebetween positioned close to the source of said beam, means for producing an alternating deflection 30 charge on said electrodes by collection of electrons from said beam, means for regulating the frequency of deflection, and means for utilizing the excess of electrons over the power necessary for deflection. 35

8. In a cathode ray tube having an envelope containing a cathode and anode adapted to project a beam of cathode rays into space, a pair of electrodes positioned close to the source of said beam and separated to allow said beam to pass therebetween, means for returning said beam to the plane of said electrodes, means for regulating the time of flight of the electrons in said beam, a tuned circuit connecting said electrodes, and means for offsetting the beam in space so that it 40 will describe a path across said electrodes during collection apart from the region wherein electrons are passing outwardly between said electrodes. 45

RUSSELL H. VARIAN.
